UNITED STATES PATENT OFFICE.

WILLIAM BEHLING, OF McDONALD, PENNSYLVANIA.

FOLDING UMBRELLA.

1,157,974.

Specification of Letters Patent.

Patented Oct. 26, 1915.

Application filed February 18, 1914. Serial No. 819,559.

To all whom it may concern:

Be it known that I, WILLIAM BEHLING, a citizen of the United States of America, residing at McDonald, in the county of Washington and State of Pennsylvania, have invented certain new and useful Improvements in Folding Umbrellas, of which the following is a specification, reference being had therein to the accompanying drawing.

10 This invention relates to folding umbrellas and has for its object to provide an umbrella of such class, in a manner as hereinafter set forth, which when not in use and closed, can be folded very compactly.

15 Further objects of the invention are to provide a folding umbrella which is simple in its construction and arrangement, strong, durable, efficient and convenient in its use, readily set up and comparatively inexpensive to manufacture.

20 With the foregoing and other objects in view the invention consists of the novel construction, combination and arrangement of parts as hereinafter more specifically described and illustrated in the accompanying drawings wherein is shown an embodiment of the invention, but it is to be understood 25 that changes, variations and modifications can be resorted to which come within the scope of the claims hereunto appended.

25 In the drawings wherein like reference characters denote corresponding parts throughout the several views: Figure 1 is an elevation of a portion of an umbrella showing a rib extended and a rib closed, and further illustrating the stick partly folded; Figs. 2 and 3 are details of the stick.

30 Referring to the drawings in detail, the stick includes an intermediate section 4, a tip section 5 and a handle section 6. The inner end of the tip section 5 has slidably connected therein a member 7 to which is pivotally connected as at 8, a link 9, the latter being pivotally connected in the bifurcated 35 upper end 10 of a bar 11, which projects from the upper end of the intermediate section 4. The elements 7, 9 and 11 can be shifted into the tip section 5 until the upper end of the intermediate section 4 abuts 40 against section 5 within a sleeve 12 carried on the lower end of the tip section 5. The sleeve 12 is formed with a notched extension 13 which is adapted to receive a pin 14^a on the intermediate section 4, and when said 45 pin 14^a is in engagement with the notched extension 13, the intermediate section 4 is

5 maintained in abutting engagement with the section 5. The handle section 6 is slidably mounted upon the intermediate section 4 and the latter is formed with a notch 14 in which 60 engages a spring latch 15 for maintaining the handle section 6 in an extended position. The elements 7, 9 and 11 provide what may be termed a hinge connection between the sections 4, 5 whereby the said sections can 65 be folded.

70 The tip section 5 has attached thereto a notch 16 and slidably mounted upon said tip section is a runner 17 provided at its upper end with a notch 18, having pivotally connected thereto the lower ends of the spreaders 19. Slidably mounted upon the runner 17 is a flanged collar 20 having attached to its upper flange 21 the lower ends of flexible members 22, these latter having their upper 75 ends connected near the outer ends of the spreaders 19. Pivotally connected to the lower flange 23 of the collar 20 is a spring controlled dog 24 capable of engaging in a rack 25, formed on the runner 17, for maintaining the collar 20 in the position to which it has been adjusted.

75 Secured to the notch 16 are the inner ends of inner rib sections 26. Each of the said sections has an angularly disposed inner section 27 and a right angularly disposed eye 28 at its outer end. The outer rib sections are indicated at 29 and each has its inner end formed with a right angularly disposed eye 30 through which extends the section 26. 80 The section 29 extends through the eye 28, and by such an arrangement the section 29 is slidably connected to the section 26. Pivotally connected to the lug 31 is the outer 85 end of the spreader 19.

90 Interposed between the sections 26 and the spreaders 19 are the brace-members 32, the upper end of each of the brace-members 32 being pivotally connected as at 33 to one of the angular portions 27 of the sections 26, 100 the lower end of each of the brace members 32 being slidably connected, as at 34, to a spreader 19. Each of the brace members 32 is attached to its adjoining brace members by flexible connections 35, and being thus all 105 connected together they cannot be moved outwardly farther than these flexible connections will permit.

95 The spreaders 19 are curvilinear in contour, and when the umbrella is folded the 110 spreaders are arranged against the stick, with the sections 29 positioned inwardly.

with respect to the sections 26, and the brace members will be arranged inwardly with respect to the spreaders, the flexible members 22 being interposed between the sections 5 29 and the spreaders. The collar 20 is utilized to maintain the flexible members 22 taut when the ribs are extended in the manner as illustrated in Fig. 1.

What I claim is:—

- 10 1. An umbrella comprising a stick, a runner carried thereby, a collar slidably mounted on said runner, an inner rib section having its inner end pivotally connected to the stick, an outer rib section slidably connected 15 to the inner rib section, a spreader pivotally connected to said runner and to said outer rib section, a brace pivotally attached at its upper end to the inner end of said inner rib section and slidably mounted at its lower 20 end on said spreader, and a flexible member connected to said spreader and to said collar.
2. An umbrella comprising a stick, a runner carried thereby, an inner rib section having its inner end pivotally connected to the 25 stick, an outer rib section slidably connected to the inner rib section, a spreader pivotally connected to said runner and to said outer rib section, a brace pivotally attached at its upper end to the inner end of said inner rib 30 section and slidably mounted at its lower end on said spreader, a flexible member connected to said spreader, and a collar slidably mounted on said runner and connected to said flexible member for maintaining the 35 flexible member taut when the rib is extended.
3. An umbrella comprising a stick, a

series of ribs each including an inner and an outer section slidably connected together, the inner sections being pivotally connected to said stick, a collar slidably mounted on said runner, spreaders pivotally connected to said runner and to said outer rib sections, brace members pivotally connected at their upper ends to the inner rib sections near 40 their inner ends and slidably connected at their lower ends to the spreaders, flexible members limiting the outward movement of said brace members, and flexible members connecting said spreaders to said collar. 45

4. An umbrella comprising a stick, a series of ribs each including an inner and an outer section slidably connected together, the inner sections being pivotally connected to said stick, spreaders pivotally connected to 50 said runner and to said outer rib sections, brace members pivotally connected at their upper ends to the inner rib sections near their inner ends and slidably connected at their lower ends to the spreaders, flexible 55 members limiting the outward movement of said brace members, flexible members connected to said spreaders, and a collar slidably mounted on said runner and connected to said flexible members for maintaining 60 the flexible members taut when the ribs are 65 extended.

In testimony whereof I affix my signature in the presence of two witnesses.

WILLIAM BEHLING.
